Attorney

UNITED STATES PATENT OFFICE.

ERVIN J. FLANDER, OF ONEIDA, NEW YORK.

AUGER.

1,275,889.

Specification of Letters Patent. Patented Aug. 13, 1918.

Application filed March 9, 1917. Serial No. 153,725.

To all whom it may concern:

Be it known that I, ERVIN J. FLANDER, a citizen of the United States, and resident of Oneida, in the county of Madison and State 5 of New York, have invented certain new and useful Improvements in Augers, of which the following is a specification.

This invention relates to improvements in detachable bits and it is the dominant object of the invention to provide detachable cutters for the bit, whereby, different combinations of cutters varying in size may be placed upon the bit shank for boring holes of the desired diameters.

15 The improvements in the details and arrangement of parts will be apparent from an inspection of the accompanying drawings, in connection with the specific description hereinafter contained, and wherein the 20 preferred embodiment of the invention is disclosed for the purpose of imparting a full understanding of the same.

In the drawings:

Figure 1 is a side elevation of a bit with 25 my improved cutter applied thereto;

Fig. 2 is a horizontal section through the cutter; and

Fig. 3 is a detail in perspective of one of the cutters.

30 Similar characters of reference are employed in all of the above described views to indicate corresponding parts.

Referring now more specifically to the 35 several figures of the said drawings, there is provided the usual bit shank, designated 1, the upper extremity of which is tapered as at 2 in order that the same may be inserted into the conventional stock. An enlarged portion 3 is formed upon the lower 40 extremity of the bit shank 1 and is provided

with a pair of spaced apart openings therein, the purpose of which will be presently apparent.

Cutters 4 and 5 having pairs of spaced apart openings 6 formed therein, corresponding to the openings in the enlarged portion 3 of the shank 1 are adapted to be secured thereto through the medium of screws 7. As will be noted, one of the cutting blades is provided with a scoring 45 cutter while the remaining cutter is provided with a centering point and a lifting 50 cutter.

By detachably engaging the cutters 4 and 5 with the enlarged portion 3 of the shank 55 1, it is to be understood, that cutters varying in size may be arranged upon the bit to permit the boring of holes of different diameters, thus, obviating the necessity of additional outlay for bits of different size.

Obviously, the construction shown is capable of considerable modification and such modification as is within the scope of my claim, I consider within the spirit of my invention.

I claim:

An auger, including, in combination with a shank having an enlarged flat head, a plurality of cutter blades detachably secured to the opposite sides of said head and projecting beyond the ends of the same, one of said blades having a centering point and an obliquely disposed lifting cutter provided with a curved cutting edge formed integral therewith, and the remaining blade having 70 a scoring cutter formed on the outer end of the same.

In testimony whereof, I affix my signature hereto.

ERVIN J. FLANDER.
